UNITED STATES PATENT OFFICE

2,620,506

SUCTION CLEANING TOOL WITH
ADJUSTABLE BRUSH

Edward A. Weiland, Garfield Heights, Ohio, assignor to The Hoover Company, North Canton, Ohio, a corporation of Ohio

Application April 25, 1947, Serial No. 743,788

6 Claims. (Cl. 15—373)

1

The present invention relates to a surface-cleaning tool adapted for use with a suction cleaner.

An object of the invention is to provide a new and improved cleaning tool.

A further object is to provide a cleaning tool comprising a brush and a suction nozzle including means positioned to be actuated by the operator to raise and lower the brush out of and into surface contacting position, respectively.

Still another object is to provide a simple brush adjusting device which is rotatable on and is secured by an air conduit freely rotatably mounted on a suction air nozzle forming and brush supporting body.

Other objects and advantages of the invention will be apparent from the following specification and drawings, wherein:

Figure 1 is a plan view, partly in section, illustrating a preferred embodiment of the cleaning tool;

Figure 2 is an enlarged view of a brush adjusting mechanism for the cleaning tool of Figure 1 illustrating the retractile brush in its raised position;

Figure 3 is an enlarged view of the brush adjusting mechanism corresponding to that of Figure 2 illustrating the retractile brush in lowered position;

Figure 4 is a vertical sectional view taken along line 4—4 of Figure 3, looking in the direction of the arrows, illustrating the combination brush adjustment and nozzle construction of the cleaning tool of Figure 1; and,

Figure 5 is an exploded view of the nozzle structure and brush adjusting mechanism illustrating the parts thereof in pre-assembly position.

The embodiment of the invention herein disclosed comprises a nozzle having a body formed of a cast metal upper portion 10 and a lower portion 11 formed of a metal stamping. The upper portion 10 of the nozzle includes a top wall 12, a front wall 13, opposite end walls 14—14 and a rear wall 15. The central portion of the wall 15 includes a depending wall section 17 spaced from a wall section 16 depending from an interior construction described hereinafter. The ends of the wall section 17 and the wall 16 are joined by end walls 18—18 to define the vertical walls of a brush housing 19. A semi-circular wall 20 depends from the top wall 12 of the body 10 to define in part an outlet 21 to a cylindrical socket 22 positioned above the brush housing 19. The socket 22 forms the journal or

2

swivel for a rotatable air conducting elbow 23 which forms the means by which the cleaning tool structure may be connected to a source of suction, such as a suction cleaner, through a hose or conduit, not shown.

The lower portion 11 of the cleaning tool body has a front lip 25 and a rear lip 26 which merge at their opposite ends into nozzle end lips 27—27 to define a suction nozzle inlet 28. A portion 10 29 of the opposite ends of the front and rear nozzle lips form supporting surfaces or shoes which lie in a plane lower than the intermediate portion of the front and rear lips. The rear lip 26 slopes upwardly and rearwardly, while the 15 end lips 27—27 and the adjacent portions 29 are convexed for inclining the nozzle rearwardly during cleaning operation. The rear nozzle lip 26 is provided with an upstanding flange 30 extending throughout the length of the nozzle. A portion 31 of the flange 30 abuts the lower edge 32 of the front wall 16 of the brush housing 19. Extending laterally of the flange 30 at opposite 20 ends of the brush housing 19 are spaced shoulders 35—35 each of which has an upstanding rear flange 36 abutting the lower edge of the rear wall 15 of the upper body portion 10 and the end walls 18—18 of the brush housing 19. Each of the shoulders 35—35 is arched upwardly from the end lips 27—27 and terminates at the end 25 walls 18—18 of the brush housing 19 in the upper body portion 10. A flange 38 extends upwardly from the front nozzle lip 25 into engagement with the front wall 13 of the body portion 10. The flange 38 merges into the flange 30 of the rear nozzle lip at the ends of the cleaning tool 30 where it abuts the end walls 14—14. The nozzle lips 25 and 26 terminate in upstanding walls 41 and 42 which join a top wall 43 to define an air passageway 40 above the nozzle inlet 28. A portion 40 of the walls 42 and the central flat portion of the wall 43 is cut away to abut the lower edges of the wall 20 and to form an air passageway 46 communicating the air passage 40 and the elbow 23 through the outlet 21. The portions 45 10 and 11 of the nozzle body are removably attached together by a plurality of screws not shown threaded into lugs depending from the top wall 12.

A furniture guard 50 of rubber or other suitable material is arranged along the front wall, the ends of the top wall and rear wall of the cleaning tool, and is provided with a plurality of spaced lugs 51 which are inserted in marginal slots 52 formed in the lower edges of the walls 55 of the upper body portion 10. The outer up-

standing flanges 36 and 38 of the lower body portion 11 abut the lugs 51 to secure the furniture guard in position. As it is illustrated in Figures 2 to 5, inclusive, the furniture guard 50 ends at an opening formed in the rear wall 17 of the brush housing 19.

The brush housing 19 is completely arranged in the upper nozzle body portion 10 and referring to Figures 2 to 5, inclusive, is defined at its top by a bottom wall 55 of the socket 22 and walls 56-58 extending from the socket 22 to the housing end walls 18-19. The walls 56 are provided with shoulders 57 for threadably receiving studs 58 on which is slidably mounted an elongated brush back 60 of a brush 61 and in which are seated tufts or bristles 62. The brush 61 is spring-biased upwardly to its retracted position, shown in Fig. 2, by resilient means, compression spring 63 abutting shoulders 64 of the brush back 60 and the screw heads of the studs 58. The lowered position of the brush is shown in Figure 3 with the spring 63 compressed. For the purpose of simplification of the disclosure, a simple form of brush back 60 has been disclosed which is not adaptable to adjust the brush back when the brush bristles 62 have become worn. However, it is within the scope of the invention to provide for brush bristle wear by modifying the brush back construction in a manner, for example, as disclosed and claimed in the above mentioned copending application. Other expedients of the prior art for compensating for brush bristle wear may be used without departing from the scope of the invention.

Referring particularly to Figures 2 to 5, inclusive, the novel brush adjusting mechanism and swivel lock between the elbow 23 and the nozzle body will now be described. The swivel joint between the socket 22 and the elbow 23 comprises an annular member 65 having a lap joint construction 66 complementally formed with respect to a recess construction 67 of the socket 22, as shown in Figure 4. The annular member 65 has integrally formed thereon a pedal or actuating means 68 and a cam means 69.

Referring to Figures 3 to 5, inclusive, there will now be described the steps in assembling the elbow 23 into the complementally formed socket 22. With the dismantled parts as shown in Figure 5, the annular rotary cam 65 is mounted in the recess 67 in the position as shown in Figure 3 with the cam 69 lying in the recess 73 between the spaced portions of the wall 17-17 and engaging the top of the brush back 60 in the housing 19. The annular recess 67 and journal wall 74 of the socket 22 are cut away at 75 above the brush housing to provide for arcuate movement of the cam 69 which projects forwardly of the ring 65 as best shown in Figure 4. The ring 65 is provided with a slot 76 which is aligned with a slot 77 in the journal wall 74 when the parts are positioned as shown in Figures 3 to 5. The slots 76 and 77 then provide a channel from the exterior of the body 10 to the interior annular groove 72 in the journal wall 74. The connecting elbow 23 is provided with a bearing portion 70 which bears on the journal wall 74 to mount the elbow 23 rotatably on the body 10 when the parts are assembled as in Figure 4. A locking pin 71 projects from the bearing portion 70 of the elbow 23. To assemble the elbow 23 with the body portion 10 the elbow 23 is rotated 180° from the position shown in Figure 5 and is inserted into the socket 22 with the pin 70 passing through the aligned slots 76 and 77 into the an-

nular groove 72. The elbow is then rotated to a normal position which rotates the pin 70 in groove 72 to lock the elbow 23 and ring 65 to the body portion 10 with the bearing portion 70 rotatably mounted in the journal wall 74. An annular shoulder 78 on the elbow 23 engages the outer face of the ring 65 to secure the ring in the recess 67. The parts thus assembled are secured against undesired disassembly and the elbow 23 and ring 65 are freely rotatable with respect to each other and the body portion 10. The springs 63 maintain the brush back 60 in firm engagement with the cam ring 65 to prevent undesired rotation thereof. It is to be understood that it is within the scope of the invention that, by changing the shape of the cam 69 the wear of the brush tufts 62 may be suitably compensated for in the cleaning position of the brush, as illustrated in Figure 3.

In operation, the elbow 23 is connected to an unshown hose, the opposite end of which is connected to a source of suction as a suction cleaner to create suction in the nozzle inlet 28. The nozzle lips 25-26 glide along the surface being cleaned and dirt-laden air is drawn through the suction inlet 28, suction passageway 40, outlet 46 and the elbow 23 to an unshown dirt filter. It will be noted that the suction air passageway 40 is substantially triangular in cross-section in that its sidewalls 41 and 42 and top wall 43 converge uniformly toward the outlet 46 to provide a smooth interior for passage of the dirt-laden air.

When it is desired to utilize the brush 61 the operator rotates the ring 65 clockwise as viewed in Figures 2 and 3. This engages the cam 69 with the brush back 60 and lowers the brush with respect to the body 10 against the bias of the springs 63. The nozzle body may then be rotated about the convex shoes or gliding surfaces 29 to engage the brush with the surface being cleaned with the desired degree of force. The brush is most efficacious in loosening debris such as thread, hair or lint which is removed by the air stream after loosening by the brush. If it is not desired to use the brush, the ring 65 is rotated by the operator in a counterclockwise direction, as viewed in Figures 2 and 3, to remove the cam 69 from engagement with the brush back 60. When this is done the springs 63 raise the brush in the housing 19 so that the same is too high to contact the surface being cleaned and the tool is then used as a straight suction nozzle. Rotation of the ring 65 is easily accomplished by the operator by applying a force to the pedal 68. The cam 69 may if desired be modified to include a plurality of rest surfaces so as to compensate the brush for wear. The brush is readily removed from the tool body by removing the studs 58.

The elbow 23 and cam ring 65 may be disassembled from each other and the tool body 10 by rotating the parts to a position in which the slots 76 and 77 and the pin 70 are aligned. Since this requires placing the elbow 23 180° from the position illustrated in Figure 4 accidental disassembly of parts is impossible during ordinary use and storage of the tool.

From the above description, it will be apparent that there has been disclosed a vacuum cleaning tool combining the features of advantage enumerated as desirable, and it is to be understood that while there has been illustrated and described the preferred embodiment of the invention, it is not desired to be restricted to the exact details of construction shown and described as

obvious modifications will suggest themselves to one skilled in the art.

What is claimed is:

1. A cleaning tool comprising a body portion having a socket, means defining a suction nozzle in said tool and an air pasageway communicating with said socket and said nozzle, an air conduit rotatably mounted in said socket, an open bottom brush housing in said body portion, a surface cleaning brush in said housing, mechanism for moving said brush in opposite directions into and out of surface engaging position including resilient means biasing said brush for movement in one direction and cam means including a rotatable actuating part journalled on said air conduit for moving said brush in the other direction against the action of said biasing means, and means for securing said rotatable part and said air conduit to said body portion.

2. A cleaning tool having a body portion formed with an internal cavity, means defining a suction nozzle on said body portion communicating with said internal cavity, means defining a socket on said body portion communicating with said cavity, an air conduit rotatably mounted in said socket, a surface cleaning brush, means mounting said brush for movement in opposite directions toward and away from the plane of the surface contacting portions of said tool including resilient means biasing said brush to move in one direction and brush adjusting means having an actuating part journalled on said air conduit for moving said brush in the opposite direction against the action of said resilient means.

3. A cleaning tool for suction cleaning apparatus comprising a nozzle body portion including a suction nozzle and a hollow journal, an air conduit rotatable in said journal, a surface cleaning brush in said nozzle body, and means mounting said brush for movement in opposite directions into and out of said nozzle body including resilient means biasing said brush in one of said directions and means for moving said brush in the other of said directions against the action of said biasing means, and a manually operable ring rotatably mounted on said air conduit and connected with said brush moving means to operate the same.

4. In a cleaning tool, a body, a suction air passageway formed in said body terminating in a nozzle portion, a suction air conduit rotatably mounted in said body and open to said passageway, a brush housing in said body, a surface cleaning brush in said brush housing, said body being formed with an annual recess extending around said air conduit and opening into said brush housing, means to project and retract said brush with respect to said housing includ-

ing an annular actuating element rotatably received in said recess about and journalled on said air conduit, cam means on said actuator extending into said brush housing and engaging said brush and resilient means biasing said brush into engagement with said cam means.

5. In a cleaning tool, a body, a suction air passageway formed in said body terminating in a nozzle portion, a suction air conduit rotatably mounted in said body and open to said passageway, means providing a detachable connection between said body and said air conduit, a brush housing in said body, a surface cleaning brush in said brush housing, said body being formed with an annular recess extending around said air conduit and opening into said brush housing, means to project and retract said brush with respect to said housing including an annular actuating element rotatably received in said recess about and journalled on said air conduit, cam means on said actuator extending into said brush housing and engaging said brush, resilient means biasing said brush into engagement with said cam means and shoulder on said air conduit bearing against the outer face of said annular actuating element to retain the same in said recess.

6. In a cleaning tool, a body, a suction air passageway formed in said body terminating in a surface contacting nozzle portion, means defining a socket in said body open to said passageway, an air conduit journalled in said socket, a brush on said body adapted to be moved between surface contacting and retracted positions, means biasing said brush to one of said positions, means operable to move said brush to the other of said positions against the action of said biasing means including an operator operable ring journalled on said air conduit for rotary operating movement independently of rotary motion of said air conduit.

EDWARD A. WEILAND.
